UNITED STATES PATENT OFFICE.

DENNIS D. CASEY, OF SPRINGFIELD, MASSACHUSETTS.

PUMP-BOX.

SPECIFICATION forming part of Letters Patent No. 290,211, dated December 18, 1883.
Application filed March 23, 1883. (No model.)

To all whom it may concern:

Be it known that I, DENNIS D. CASEY, a citizen of the United States, residing at Springfield, in the county of Hampden and State of 5 Massachusetts, have invented new and useful Improvements in Pump Boxes and Valves, of which the following is a specification.

This invention relates to improvements in hand-pump valves, the object being to provide an improved valve and valve-seat, and means for lifting said valve from its seat when the pump-piston is driven downward, for the purpose of letting the water out of the pump and to provide an improved valve-box.

15 In the drawings forming part of the specification, Figure I is a sectional view of the lower end of a pump-barrel having a pump-valve applied thereto embodying my improvements, the latter being shown therein in side 20 elevation. Fig. II is a side elevation of the valve and its box, partly in section. Fig. III is a plan view of the valve-box, with the bail removed. Fig. IV is a plan view of the bottom, and Fig. V of the top, of the valve.

25 In the drawings, A is the pump-barrel. D is the pump-box. B is the exterior leather packing on said box. h is a packing-nut. h' is a perforated cross-bar or valve-stem guide on said nut. v is the valve-disk. o is the 30 valve-stem. s is a nut. x is a washer. w is an elastic valve-face ring. m is the raised valve-seat. c is the bail on box D. e e are stops on bail c. d is the valve-lever. n is a lever-staple on valve v.

35 The pump-barrel A is of the usual form, having its lower part made tapering, to receive the valve-box. The valve-box D is made tapering, to correspond with the shape of that part of the barrel A in which it is fitted, 40 as shown. It is common to make the surface-packing of the box D of a strip of leather wound around it and secured thereon by nails or rivets. My box-packing B is formed up from a suitable piece of leather into a cup 45 form, open at the bottom, and fitted to the box D, as shown in Fig. II. The lower end of the opening through box D is screw-threaded, and the packing-nut h is fitted to screw therein. Said nut h has a flange thereon, between which and the lower end of box D the lower portion of the packing B is clamped to the box when nut h is screwed up,

and thereby said packing is firmly secured to said box, and in case of need the packing can be very easily renewed. A perforated cross-bar, h', across the bottom of nut h forms a guide for the valve-stem o. On the upper face of the valve-box D, around the border of the opening through it, is formed the raised valve-seat m, having a curved or half-round edge. 60 The valve-disk v is provided with a downhanging stem, o, which is screw-threaded and has a nut, s, fitted thereto, and the upper face of said disk has fixed thereupon, near one edge, the lever-staple n. The elastic ring w, which 65 is made preferably of rubber, constitutes the face of the valve, and is secured to the under side of the disk v by the nut s and washer x in a position concentric with the edge of the raised seat m. The box D has thereon the bail 70 c, to the upper part of which is pivoted the valve-lever d, one end of which passes through the staple n on the valve, and its opposite end projects above the crown of the bail c. Two stops, e e, are provided on the inner sides of 75 bail c, to govern the rise of the valve. The form of the seat m prevents any accumulation of sand between its edge and the ring-face of the valve, as is the case when a flat-faced valve is used and permitted to act on a flat seat; and 80 the forms of said ring-face w and seat m, together with the elastic nature of said ring, adapt them to so adjust themselves one to the other as to make a tight joint.

The construction of the valve-box and valve 85 herein shown, whereby the latter is adapted to lift vertically quite clear from the valve-seat, provides for a much more unobstructed water-passage through said box than when the valve is, as usual, hung on one side of the 90 box, constituting a clapper-valve.

What I claim as my invention is—

In combination, the box D, having the raised seat m thereon, and the bail c, provided with the stops e e, the packing nut h, having the 95 guide h' across it, the valve v, provided with the stem o and staple n, and having the elastic ring-face w secured thereto, and the lever d, pivoted to said bail, substantially as set forth.

DENNIS D. CASEY.
